WAD CUTTING BULLET AND METHOD OF
MAKING SAMEDouglas B. Wesson, Longmeadow, Mass., assignor
to Smith & Wesson, Inc., Springfield, Mass., a
corporation of Massachusetts

Application April 5, 1934, Serial No. 719,151

4 Claims. (Cl. 86—24)

This invention relates to improvements in what are known as wad cutting bullets, and to improvements in methods and apparatus for making bullets of this character. In order to obtain 5 definitely and accurately marked targets it is desirable that the bullets cut material from the target instead of merely wedging their way through. The usual form of bullet removes little or no material from the target, particularly in 10 the smaller calibers, merely bending the major portion of the material outwardly to form a ragged hole. Generally cylindrical bullets with a right angled flange at their maximum diameter and a button-like head have previously been proposed as a remedy, and have proved comparatively satisfactory in the larger calibers. In 15 small calibers, however, while these prior wad cutting bullets have made clean holes in the target, they have been so erratic in their accuracy 20 that they have not been suitable for target shooting.

I have found that if the bullet is maintained in its normal shape and an annular cutting fin is formed on the ogive at a point where the 25 diameter of the fin will lie within the maximum diameter of the bullet, a clean cutting of the target will be obtained with no effect upon the accuracy of flight of the bullet. The fact that such a pronounced effect will be obtained from a cutting fin of lesser diameter than the bullet is surprising, and I believe that the explanation is 30 found in the distortion undergone by the bullet in its travel through the barrel. Due to the reaction of the bullet's inertia to the force of the 35 explosion the bullet is compressed in length, and the ogive is shortened and its larger portion made more nearly the same size as the cylindrical portion of the bullet. This of course brings the fin out more nearly to the full diameter of the bullet, 40 and thus in correct position to cut the target. Were the fin to be made initially of too large a diameter, it would be brought forcibly into contact with the barrel by the compression of the bullet, and its cutting edge destroyed or blunted. 45 On the other hand, if the cutting fin is formed too far down on the ogive, the compression of the bullet cannot bring it into a position to cause the maximum cutting action. The exact position, however, is by no means critical, as a substantial removal of the frayed edges of the hole 50 will be secured even with the fin a considerable distance down the ogive. In any case the strength of the explosive charge and the softness of the metal of which the bullet is made will have a direct bearing upon the amount of compression 55

given to the bullet, and hence upon the ultimate position of the cutting fin. No dimensional rules can be given, therefore, without knowing the particular nature of the ammunition to which the invention is to be applied. 5

The cutting fin can if desired be formed upon the bullet during its manufacture. For several reasons, however, it is preferable to form the cutting fin immediately before firing. Each marksman has his own favorite brand of ammunition, 10 and it is therefore desirable to provide some method and apparatus by which he may adapt that particular ammunition for wad cutting. The cutting fin employed in accordance with this invention can be made sharper and thinner, and 15 thus more effective and less likely to deflect the bullet, if it does not have to withstand the handling and concussions inevitable in manufacturing and packing operations. For these reasons I prefer to form the cutting fin on the bullet shortly 20 before the time of its use; and have provided for this purpose a portable apparatus which can be employed at the target range if desired, and which can be adjusted to give the size of fin best suited to the preferences of the user. 25

The invention will now be described in accordance with the accompanying drawing, in which

Fig. 1 is a side elevation of a holding or chucking apparatus for the cartridge;

Fig. 2 is a side elevation of the fin cutting part 30 of the apparatus;

Fig. 3 is a section on line 3—3 of Fig. 1;

Fig. 4 is an end view, looking from the left in Fig. 2;

Fig. 5 is a side view of a cartridge the bullet of 35 which has been provided with a cutting fin in accordance with this invention;

Fig. 6 is a detail of the bullet removed from the case; and

Fig. 7 is a detail of the bullet illustrating the 40 action of the bullet compression in shifting the cutting fin.

In Figs. 5 and 6 the bullet 10 has a reduced portion 50 by which it may be fixed in the case 11 in the usual way. The cutting fin 12 is formed as 45 an annular projection or burr upon an intermediate portion of the ogive 13. As has been stated above, the location of the cutting fin is preferably within the maximum diameter of the bullet, here projected for reference as a dotted 50 line 14. When the bullet passes through the barrel it will have been somewhat compressed longitudinally, as shown in Fig. 7 by the elimination of the shoulder 50 and the presence of rifling marks throughout the length of the bullet; and 55

this will bring the burr 12 out nearly to the line 14, as shown in Fig. 7, without substantially changing its form. In the latter condition it strikes the target, the burr cutting off the torn edges produced by the puncturing action of the head 15 of the bullet. The action is noticeably greater with increased velocity, probably on account of the greater effect of the inertia of the paper edges in resisting a high speed blow.

10 The apparatus provided for forming the cutting fins or burrs on the bullets is illustrated in Figs. 1 to 4. It consists of two parts, one for holding the cartridge and the other for forming the fin. The cartridge holding part 16 has a hole 17 in one end of the same diameter as the cartridge. At the other end of the holding member 16 is a hole 18 of larger diameter, extending deeply enough into the body of the member 16 to expose a portion of the ogive of the bullet. A lateral slot 19 is formed in the member at the point where the case ends, and in this is a clamping slide 20 having a hole 21 slightly larger than the hole 17. A screw 22 is threaded into the slide and straddles the walls of the slot, so that by tightening it the slide can be drawn laterally to clamp the case and bullet simultaneously in the member 16. The member 16 is preferably knurled on its outer surface to facilitate its being held firmly.

15 30 The cutting tool shown in Figs. 3 and 4 has a body portion 25, also knurled on its outer surface, provided with a through hole 26. Into one end of this hole slides the cutting tool proper 27, held against rotation by a set screw 28 extending into a keyway 29. A threaded shank 30 extends from the cutting tool, and is screwed into a nut 31 having a threaded hole 32. The nut is provided with a head 33, preferably graduated for cooperation with an index mark on the body 25, and is held against longitudinal movement by a set screw 34 fitting into an annular groove 35 in the nut. The nut can be turned to regulate the extent to which the cutting tool projects beyond the end 36 of the body, after which it can be clamped in adjusted position by tightening the set screw 34 so that it bears against the bottom of its groove. The end of the cutting tool is preferably made conical, and is formed with a central depression 40 which fits over the end of the ogive of the bullet. If desired, teeth 41 may be formed in the conical portion of the tool to assist the action of the cutting edge 43.

20 35 40 45 50 55 60 In use a cartridge is clamped in the holder 16 by turning the screw 22, the slide 20 engaging the bullet, and preferably both the bullet and the case so as to prevent relative turning during the cutting. The shank 27 of the cutting tool is then introduced into the hole 18 of the holder, and as soon as the cutting edge 43 contacts with the bullet the tool is manually rotated to cause a circular furrow to be cut in the ogive of the bullet. Due to the shape of the cutting tool a sharp burr will be turned up at the outer side of the furrow.

The depth of the furrow, and consequently the size of the burr, can be regulated by changing the amount which the cutting tool projects beyond the shoulder 36. The bullet being soft, the cutting tool will sink into it readily until its progress is arrested by contact of the shoulder 36 with the end of the holder 16. The rim 44 of the case limits the position of the cartridge, and the shoulder 36 limits the ultimate position of the cutting tool, so that an accurate control of the size of the fin 12 can be obtained by varying the setting of head 33.

Instead of using a rotating cutting tool it is of course possible to strike up the burr by direct pressure. This is, however, more likely to disturb the relation of the bullet and the case, or otherwise to injure the cartridge, and a rotating tool is therefore preferred. Other changes in the form of the burr, the method of forming it, and the apparatus for making it, may be made without departing from the invention as set forth in the following claims.

I claim:

1. A device for forming wad cutting bullets which comprises means for holding a previously assembled cartridge, and a tool coating therewith for striking up an outstanding cutting fin on the ogive of the bullet.

2. A device for forming wad cutting bullets which comprises clamping means for holding a previously assembled cartridge, a cutting tool coating therewith for striking up an outstanding cutting fin on the ogive of the bullet, and means for adjusting positively the depth of cut given by said tool.

3. A device for forming wad cutting bullets which comprises clamping means for holding a previously assembled cartridge, said means being formed with a recess into which the bullet projects, a cutting tool fitting into said recess and formed to strike up an outstanding cutting fin on the ogive of the bullet, and a member adjustable on said cutting tool and adapted to strike against the clamping means to limit the depth of cut given to the bullet.

4. A device for forming wad cutting bullets which comprises clamping means for a previously assembled cartridge, said means being formed with a recess into which the bullet projects, a cutting device having a body, a tool slideable in the body and adapted to enter the recess in the clamping member, the end of the tool being formed with a bullet receiving recess and a circular cutting edge, an adjusting member secured in the body against longitudinal movement and having screw threaded engagement with the tool to change its degree of projection from the end of the body and thereby the depth of its penetration into the recess in the clamping member, and means for securing the adjusting member in adjusted position.

DOUGLAS B. WESSON.
